METHOD AND APPARATUS FOR OPERATING WELLS

Application filed November 15, 1937. Serial No. 233,348.

This invention relates to a method and apparatus for casing and operating wells, such as oil and gas wells.

In the drilling of wells, such as oil and gas wells, the well is frequently drilled through a number of spaced apart formations which will yield oil or gas. With the present apparatus and method for operating and casing such wells extreme difficulty is experienced in producing oil or gas from more than one of such formations. Ordinarily in the operation of oil or gas wells the production of the well takes place only from the lowest formation which is encountered in drilling the well. In the operation of such wells, a string of casing is installed in the well leading from the surface of the well substantially to the formation from which gas or oil is to be produced. This casing is set at its lower end usually by a cementing process in order to seal the lower formation from communication with the upper formations so that water or other fluids from above can not migrate into the lower formation. This sealing and cementing of the casing at its lower end ordinarily requires that prior thereto mud fluid be circulated in the well and after the sealing operation this mud fluid is left around the casing which imposes a pressure upon all the upper formations preventing the fluids therein from entering the well bore around the installed casing.

An object of the present invention is to provide a method and apparatus for operating wells by which it is rendered possible to produce fluids from two or more formations encountered in the drilling of a well by means of a single casing installed in the well.

Another object of the present invention is to provide a method and apparatus for casing and handling wells by means of which the casing installed in the well may be opened at a desired point between the ends of the casing for establishing communication between the inside and exterior of said casing and also to provide a method and apparatus by which such opening may be closed when desired without sealing or otherwise effecting the formations on the exterior of the casing.

Another object of the present invention is

to provide a method and apparatus for producing fluid from two different formations in a well without the pressure of the fluid of one formation being imposed upon the fluid from the other formation.

Frequently in drilling an oil well a producing sand, either gas or oil, is encountered but it is determined to drill the well deeper down to a lower oil or gas sand. When this is done ordinarily production can be had only from the lower oil or gas sand, the upper oil or gas sand being closed off by the casing lowered to the lower formation. The hydrostatic pressure of the hydraulic fluid in the well is imposed upon the upper oil or gas bearing sand so that the oil or gas in such formations is prevented from rising to the surface of the well around the casing which is lowered to the lower formation. In accordance with the method and apparatus of the present invention, when the casing is installed at the lower formation and before production is made to take place from such lower formation, the casing is opened at a point opposite the upper oil or gas bearing formation and the hydraulic fluid around the casing is drawn into the casing by a bailer or other means. In this way the hydraulic pressure holding the oil or gas on the upper formation is removed and the oil or gas will rise around the casing. The method and apparatus of the present invention provide means by which this casing may be again closed without resealing the upper formation and thereby production may then be established through the casing from the lower formation so that production takes place from both formations at the same time without necessarily the pressure upon either formation being imposed upon the other formation.

The method and apparatus of the present invention also provide a means by which the large hydrostatic pressure on the oil string may be removed in cases of extremely deep wells so that an oil string of less strength than that which is ordinarily required may be employed. When a well is drilled by the rotary method to the depth of, for example 6,000 feet, the pressure of the

hydraulic drilling fluid in the lower portions of the well is several thousand pounds per square inch. When the oil string is first lowered into such a well, the hydraulic fluid exists equally on the inside and outside of the string and does not tend to collapse the same. When, however, the string is seated at its lower end and then bailed out to start production from the well, the pressure on the lower end of the string due to the hydraulic fluid surrounding the string is very great. At present there is no satisfactory means by which the drilling fluid around the well string may be removed to eliminate or reduce this pressure. By the process and apparatus of the present invention the well is operated so that the oil string may be opened up after the same is seated and this hydraulic fluid removed from the well bore all or in part by withdrawing the same through the inside of the oil string after which the oil string may be again closed.

The present invention also provides a means by which the entire exterior or a large portion of the exterior of a string of casing or oil string may be re-enforced with cement. By the methods now in use it is possible to force cement down through the casing and up around the exterior of the casing to a height of about 2,000 feet. In wells of greater depth than 2,000 feet it is generally necessary to leave the exterior free from any re-enforcing cement. By the process and apparatus of the present invention the casing may be opened as desired at different points to force additional cement up around the exterior of the casing and accordingly the casing may be re-enforced with cement to any desired height up to as high as the surface of the well.

The present invention also provides a method and means for operating wells whereby different fluids encountered in drilling the well may be made to assist one another in their elevation to the surface of the well. Frequently oil is found in the formation under insufficient pressure so that the same will flow without pumping to the surface. By supplying additional gas in form of jets to the said oil, the same may be elevated to the well by the lifting action of the gas. The present invention provides a means by which, when both an oil and gas sand are encountered in the same well, the gas from the gas sand may be suitably introduced into the oil being withdrawn from the oil sand so that the gas operates as a means for assisting the elevation of such oil.

Various further objects and advantages of the present method and apparatus for casing and handling wells, such as oil wells, will be understood from the description of a preferred form or example of a method and apparatus embodying the invention. For this purpose there is hereinafter described with

reference to the accompanying drawings the preferred method and apparatus.

In the drawings:—

Figure 1 represents an elevation in vertical section of an apparatus for casing or handling wells in place in a well hole;

Figure 2 is an enlarged elevation in vertical section of a slip-joint and lateral valve employed in the present invention;

Figure 3 is a section on the line 3—3 of Figure 2;

Figure 4 is an elevation similar to Figure 1 with the apparatus in a different operating position; and

Figure 5 illustrates a modified form of the invention showing the apparatus in place in a well hole and mainly in vertical section.

Referring to the drawings,—1 indicates a string of pipe or casing in place in a well hole, the string of pipe or casing 1 generally being referred to in the art as an oil string.

Said string of pipe is connected with or includes a section of pipe 2 which is provided at its lower end with a left hand external thread 3. Said thread is indicated as screwed into an internal left hand thread 4 provided by a swedge nipple 5. Said swedge nipple 5 is also a part of the oil string 1. The nipple 5 is indicated as provided with an extension or guide 6 of any suitable length which extends upwardly above the threads 4.

Said extension 6 is provided at its upper end with an internal flange 7 or other means forming the stop adapted to engage an external annular shoulder 8 on the pipe 2 for limiting the motion between the nipple 5 and the section of pipe 2 when the threads 3 and 4 are separated.

The stop 7 and the shoulder 8 are indicated as preferably formed to provide a clutch face so that in the extended position of the parts 2 and 5 there is provided a clutch by means of which the pipe or casing below the nipple 5 may be rotated by rotation of the casing above the nipple 5 after the threads 3 and 4 have been separated. This permits a

number of devices such as are shown in Figure 2 to be included in a single string of casing and each of such devices operated as required.

The extension 6 of the nipple 5 above the threads 3 and 4 is shown as preferably provided with a plurality of perforations or apertures 9 so that when the threads 3 and 4 are separated and the pipe section 2 elevated relative to the nipple 5, fluid may be passed through such openings and thereby communication established between the interior and exterior of the casing 1 at a point opposite the nipple 5. The device comprising the section of casing 2 and swedge nipple 5 is thereby formed to operate both as a slip-joint clutch and as a lateral valve or means for opening the casing.

Now referring to Figure 1 of the drawings, the apparatus is indicated positioned in order

100 of the parts 2 and 5 there is provided a clutch by means of which the pipe or casing below the nipple 5 may be rotated by rotation of the casing above the nipple 5 after the threads 3 and 4 have been separated. This permits a

105 number of devices such as are shown in Figure 2 to be included in a single string of casing and each of such devices operated as required.

The extension 6 of the nipple 5 above the threads 3 and 4 is shown as preferably provided with a plurality of perforations or apertures 9 so that when the threads 3 and 4 are separated and the pipe section 2 elevated relative to the nipple 5, fluid may be passed through such openings and thereby communication established between the interior and exterior of the casing 1 at a point opposite the nipple 5. The device comprising the section of casing 2 and swedge nipple 5 is thereby formed to operate both as a slip-joint clutch and as a lateral valve or means for opening the casing.

Now referring to Figure 1 of the drawings, the apparatus is indicated positioned in order

110 of the parts 2 and 5 there is provided a clutch by means of which the pipe or casing below the nipple 5 may be rotated by rotation of the casing above the nipple 5 after the threads 3 and 4 have been separated. This permits a

115 number of devices such as are shown in Figure 2 to be included in a single string of casing and each of such devices operated as required.

The extension 6 of the nipple 5 above the threads 3 and 4 is shown as preferably provided with a plurality of perforations or apertures 9 so that when the threads 3 and 4 are separated and the pipe section 2 elevated relative to the nipple 5, fluid may be passed through such openings and thereby communication established between the interior and exterior of the casing 1 at a point opposite the nipple 5. The device comprising the section of casing 2 and swedge nipple 5 is thereby formed to operate both as a slip-joint clutch and as a lateral valve or means for opening the casing.

Now referring to Figure 1 of the drawings, the apparatus is indicated positioned in order

120 of the parts 2 and 5 there is provided a clutch by means of which the pipe or casing below the nipple 5 may be rotated by rotation of the casing above the nipple 5 after the threads 3 and 4 have been separated. This permits a

125 number of devices such as are shown in Figure 2 to be included in a single string of casing and each of such devices operated as required.

to carry out one preferred method of handling or operating a well. The well bore is indicated as including an upper sand 10 below which there is a water sand 11 and below the 5 water sand 11 is indicated a shale formation 12 on the top of a gas sand 13. Below the gas sand 13 is indicated another shale formation 14, then a water sand 15, a further shale formation 16 and finally an oil sand 17. 10 Ordinarily in order to produce oil from the sand 17 it would be necessary to seal off the gas sand 13. This is for the reason that in order to protect the oil formation 17 from the water sand 15 it is necessary to seat or seal 15 the lower end of the casing 1 in the bottom of the well, and it is also necessary that cement be forced around the exterior of the casing 1 up above the water sand 15 in order to prevent the water from such sand entering the well 20 hole. The placing of the cement which is indicated at 18 around the lower end of the casing 1 and around the water sand 15 customarily requires that mud fluid first be pumped down the string 1 and up around the string in 25 order to effectively remove from back of the string any obstructions which would prevent fluid cement pumped down casing 1 from rising around the casing. This operation leaves the well hole both inside and outside of the 30 casing 1 filled with mud fluid. The cement is then placed in the casing 1 and forced down the casing excluding the fluid mud until it reaches the position indicated at 18. The well is then held so that the cement will set in 35 this position with the result that above the cement 18 around the casing 1 there is mud fluid which ordinarily extends to the top of the well. The pressure of such mud fluid upon the gas sand 13 is generally sufficient to 40 prevent the gas leaving said sand and producing around the casing 1.

When it is desired with the present invention to save the gas sand 13, there is set in the well, before the casing 1 is lowered, a 45 string of casing 19 down below the lower end of the upper water sand 11. This casing is then seated and cemented in place by cement as indicated at 20 to shut off the water sand 11 from the balance of the well bore. The 50 well bore is then drilled through the remaining formations and the casing 1 lowered in place. The casing 1 as provided has inserted in it a lateral valve or slip-joint including the section of pipe 2 and swedge nipple 55 1 at a point in the casing 1 which will permit these parts to be disposed opposite the gas sand 13. During the lowering of the casing 1 the threads 3 and 4 are made up so that communication laterally through the casing 60 1 is cut off. The casing 1 is lowered into place so that its shoe 21 is at the top of the oil sand 17 and then the same is seated and sealed in place by means of cement. When the cement 18 has set so as to shut off the 65 water sand 15, the upper section of the casing

1 is turned in a right hand direction which tends to tighten up all of the couplings in the casing except the threads 3 and 4 and serves to unscrew such threads so that the section of casing 2 may slide in the swedge 70 nipple 5. After the threads 3 and 4 are unscrewed the upper part of the casing 1 is elevated thereby permitting communication through the side of the string and fluid mud passes from the interior to the exterior of the string or vice versa through the perforations 75 9. Figure 4 illustrates the apparatus in this position. A bailer may then be lowered into the string 1 and the casing or string 1 bailed out so as to draw away from the sands 13 80 the hydraulic fluid around the casing 1 above said sands. The gas formation 13 will thereby be relieved from pressure of fluid in the well and the gas from the formation 13 will be permitted to rise up around the string 85 1 between the casings 1 and 19 to the top of the well. After production from the gas sand is started in this way, the upper section of casing 1 may be again lowered and the casing rotated to again make up the threads 90 3 and 4. Thereby the interior of the casing 1 is effectively sealed off from the sand coming from formation 13 while at the same time the closing of the casing has not prevented the free flow of gas from sand 13 up around 95 the casing 1.

After the casing 1 is again closed the usual practice may be resorted to for establishing production from the oil sand 17 through the casing 1. Such steps generally consist in 100 drilling through the cement at the bottom of the casing and otherwise operating to open the production.

The object of having a left hand thread between the section of casing 2 and nipple 5 105 is obvious. It can be seen that all of the pipe in the string 1 which is coupled with couplings having right hand threads will be made up tighter when the pipe is turned in order to unscrew the left hand threads 3 and 4. As a result there will be no danger of unscrewing the right hand threads in the string of pipe when the string is turned to the left for the purpose of again making up 110 the left hand threads 3 and 4. It is obvious, of course, that the device could be made having a right hand thread at 3 and 4 and operated by making up that thread or connection less tight than all of the other connections are made up. In certain cases the threads 3 and 4 may be omitted and a ground seat provided between the section of casing 2 and nipple 5 in which case the weight of casing or pipe 1 above the seat would be sufficient to positively close the same when desired. 115 120 125

Now referring to Figure 5, a modified form of the invention is illustrated for use where it is desired to have fluid from one formation assist fluid from another formation in 130

its elevation from the well hole. The apparatus is illustrated in use in a well hole in which there is an upper oil bearing formation 22 and a lower gas producing formation 24 with an intermediate water sand 23. The apparatus is shown as comprising a string of casing 28, the lower end of which is provided with a shoe 29 and the shoe 29 is indicated as set with cement 30 in the bottom of the well hole, the cement 30 being forced up around and above the water sand 23 so as to exclude the water from the sand 23 passing either upwardly into the oil sand 22 or downwardly into the gas sand 24.

15 The casing 28 is indicated as including the valve shown in Figure 2 which provides a means for forming an opening in the side of the casing, the same including the swedge nipple 5^a and the section of pipe 2^a having 20 left hand threads 3^a and 4^a adapted to be threaded together for locking the same in the closed position. The swedge nipple 5^a is indicated as provided with a guide section 6^a 25 provided with apertures 9^a for establishing communication between the interior and exterior of the string 28 when the threads 3^a and 4^a are separated.

Within the lower portion of the string of casing 28 there is positioned a section of pipe 30 25 extending down to the gas producing formation 24 and provided with a packer 27 engaging the inner wall of the lower portion of the string 28 below the valve so as to shut off the oil sand 22 from communicating with 35 the gas sand 24 around the casing 25. The upper end of the casing 25 is indicated as terminating in a jet forming nozzle 26 at a point above the valve in the casing 28.

40 With the apparatus thus illustrated, the method of operating a well is as follows:

The casing 28 with the valve therein is first lowered into the well, the valve being positioned in the casing so that it will be located adjacent the oil sand 22. The casing 28 is then cemented in place to seal off the water sand 24 and the lower portion of the well bored out for establishing communication with the gas sand. The pipe 25 and its 45 packer are then lowered in position and the upper section of the casing 28 is turned to the left to break the threads 3^a and 4^a and permit the oil from the formation 22 to enter the casing 28. As the oil enters the casing 28 through the perforations 9^a and passes up 50 around the nozzle 26, the gas passing from formation 24 is injected into the oil thereby assisting the elevation of said oil to the surface of the well. By injecting the gas from the formation 24 into the casing 28 in the form of an upwardly directed jet, the pressure of the gas in formation 24 is not applied to the oil bearing formation 22 but such pressure in place produces a suction in 55 the casing 28 tending to draw in the oil from the formation 22. In this manner the

method and apparatus of the present invention provide a means by which production from two different formations may take place simultaneously and provide also a means by which the fluid from one formation 70 assists the production of fluid from another formation.

While the method and apparatus for handling wells herein described are well adapted to carry out the objects of the invention, 75 it is understood that various modifications and changes may be made without departing from the invention and the invention includes all such modifications and changes as come within the scope of the appended 80 claims.

I claim:

1. A method of operating a well comprising, lowering a string of casing into the well, cementing the lower end of the string of casing to close off the formation below the string from the space around the string, establishing communication between the space around the string above the cement seal and the inner bore of the casing in order to permit mud fluid to drain into the string, interrupting such communication after the mud fluid has drained into the casing, drilling out the cement at the bottom of the well hole to establish communication through the lower end of the string, and thereafter again establishing communication between the space around the string above the cement seal and the inner bore of the string, whereby two producing strata may produce into one 100 string.

2. A method of operating a well which comprises, lowering a string of casing into the well, cementing the lower end of the string to close off the formation below the string from the space around the string and to temporarily close the lower end of the string, establishing communication between the space around the string above the cement seal and the inner bore of the casing in order 105 to permit mud fluid around the string to pass into the string, interrupting such communication after the fluid has drained into the casing, drilling out the cement at the bottom of the well hole to establish communication through the lower end of the string, and thereafter again establishing communication between the space around the string above the cement seal and the inner bore of the string whereby two producing strata may 110 produce into one string.

3. A method of producing fluids from two spaced apart formations encountered in drilling a well which comprises, lowering into the well a string of casing to the lowered formation, cementing the lower end of the string to close off the formation below the string from the space around the string, establishing communication between the space around the string and interior of the string 115

until mud fluid around the string has drained into the string and the upper formation is in condition to drain oil into the string, then interrupting communication between the space around the string and the interior of the string, drilling out the cement at the bottom of the well hole to establish communication through the lower end of the string and the lower productive formation, thereafter again establishing communication between the space around the string above the cement seal and the inner bore of the string whereby two producing strata may produce into one string.

15 Signed at Los Angeles, Calif., this 9th day of November, 1927.
